UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

CARBON PAPER.

Original application filed January 27, 1920, Serial No. 354,475. Divided and this application filed February 12, 1921. Serial No. 444,307.

To all whom it may concern:

Be it known that I, JOHN WALDHEIM, a citizen of the United States, residing in Elizabeth, in the county of Union and State 5 of New Jersey, have invented certain new and useful Improvements in Carbon Paper, of which the following is a specification.

This invention relates to carbon-sheets or 10 duplicating material to be used between work-sheets in manifolding upon a typewriting machine. The invention may be used in connection with combined typewriting and computing machines which perform addition and subtraction.

15 It is customary in typewriting machines to use a bichrome ribbon having black and red color-stripes, and, when a computing device is used, the ribbon mechanism is usually connected to the computing mechanism in 20 such a way that any numbers that are subtracted are typed in red upon the work-sheet; thus the work-sheet bears its own evidence that such numbers have been subtracted by the computing mechanism.

25 This expedient, however, has been necessarily limited to the single sheet upon which the ribbon directly prints; and the difficulty has existed that on the carbon copies, which are almost invariably manifolded at the 30 same time as the ribbon copy, there is nothing to indicate whether any particular number has been written in black or in red; that is to say, in computing, there is nothing to indicate whether it has been added or subtracted by the computing mechanism.

Many efforts have been made to avoid this 35 difficulty. It has been proposed to have large figure types in typewriting-computing machines, which are called into use only 40 when subtraction is being performed by the computing mechanism, so that the carbon copies will show by the large figures thereon that certain numbers were subtracted.

It has also been proposed to print a special 45 sign before each number that is to be subtracted, so that the carbon copies shall give evidence accordingly.

It has also been proposed that a special 50 mark shall be printed under each digit that is typed, where such digits are subtracted.

The object of my invention is to provide for a distinction to be made upon the carbon copies of the main or original work-sheet, without necessitating the use of a

special set of types, or a special sign or other 55 special device or mechanism in the typewriting machine.

To attain this end and other ends, I provide means whereby the characters typed in certain columns upon the work-sheet are 60 typed in a distinctive color on the carbon copies, while the remaining numbers or data are typed in the standard color. For this purpose, all numbers that are typed in some distinctive color upon the original work-sheet are typed in a column or columns by 65 themselves as is customary. With the carbon-sheet is provided an overlying strip provided with a coating which will produce 70 typed characters of the desired distinctive color, so that any characters written in the column covered by the strip will appear in the desired distinctive color upon the carbon-sheet, the remaining portion being the 75 normal color of the carbon.

For the purpose of keeping the carbon-overlying strip in accurate alignment and register with the desired column upon the work-sheet, the carbon-sheet may be fastened thereto in such a way that the sheet and strip play the part of an integral sheet. The carbon-sheet may be of the usual width in some cases, that is to say, the width of the work-sheet, with the result that, if the carbon-sheet is properly inserted in the 80 usual manner, the strip will fall upon the proper column. To enable the strip to be adjusted to the proper column laterally of the sheet, the carbon-sheet may be provided with openings or slits through which the 85 carbon-strip may be threaded. These openings, if desired, may be arranged in pairs in extensions of the carbon-sheet beyond the end of its carbon surface. The openings may be offset or staggered, thus permitting 90 the strip to be inserted at any one of a large 95 number of positions.

Where it is desired that matter typed upon the original work-sheet in certain columns shall be omitted from the carbon copy, the 100 overlying strip, instead of being a manifolding strip, may be a strip adapted to prevent the carbon imprint from appearing on the manifold copy.

This is a division of my application, 105 Serial No. 354,475, filed January 27, 1920.

Other features and advantages will hereinafter appear.

In the accompanying drawings,

Figure 1 is a diagrammatic perspective view of an Underwood typewriting machine platen, showing a carbon-sheet embodying 5 the present invention in use.

Figure 2 is a face view of the sheet seen in Figure 1.

Figure 3 is a face view of a similar sheet, but adapted to be used to modify the mani- 10 folded work upon certain writing lines instead of in vertical columns.

Figure 4 is a view of a fragment of a carbon-sheet, showing how the detachable strip may be mounted thereon.

15 When it is desired to make a carbon copy upon a work-sheet 10 of the matter to be typed upon an original sheet 11, there is interposed between the two, before insertion into the machine, a carbon-sheet 12, so 20 that the sheets 10, 11 and 12 are fed together around the platen 13, being held thereto by the usual feed-rolls 14. This enables type-bars 15, striking through a ribbon 16, to print not only upon the outer 25 sheet 11, but also upon the inner sheet 10, the characters carried by the type-bars 15. Normally, the types print through a black stripe 17 of the ribbon 16, but, under some 30 circumstances, that is to say, in some columns, the red stripe 18 of the ribbon 16 causes red characters to be printed upon the outer work-sheet 11. To enable the characters printed by the red stripe 18 to be 35 shown in red, the carbon-sheet 12 is adapted to hold a strip of red manifolding paper 20 at the column where the red printing is effected.

To enable the strip 20 to be held in place overlying the proper column of the sheet 40 12, its opposite ends are herein shown as threaded through slits or openings 21 in extensions 22 lying outside of the reproducing surface 23, which forms the main body of the sheet 12. To hold the strip 20 45 accurately in place, it may fit the slits 21 rather closely. When thus held, its reproducing surface lies next to the work-sheet 10, thus causing the characters typed upon 50 that work-sheet to appear in red, i. e., in the color of the strip. Any typed mark of the reproducing surface 23 in this column is received upon the back of the strip 20, and therefore fails to appear upon the work-sheet 10.

55 In order to prevent the strip 20 from slipping out of the slits 21, the end of the strip may be bent over or folded back as at 24, thus enabling the strip 20 and sheet 12 to be handled as a unitary structure. If 60 it is desired that characters typed upon one column of the work-sheet 11 shall not appear upon the carbon copy 10, a blank strip 25 may be threaded through other openings 21 and have its end turned back as at 24, 65 so that it will not interfere with the ready

handling of the carbon-sheet 12 any more than does the strip 20.

Where it is desired to provide a carbon-sheet 12 which shall be used for many kinds of work, there may be provided, in addition to the outer slits or openings 21, inner slits 26 offset or staggered relatively to them. In some cases it may be found more convenient to omit one or both of the extensions 22, and have the slits 21 or 26, or 70 both, suitably placed elsewhere on the carbon-sheet.

It will be noted that the sheet 12, shown in Figure 2, has the strips 20 and 25 at the left, while, as shown in Figure 1, the strips are at the right. This is because Figure 1 is a back view of the carbon-sheet, while Figure 2 is a front view.

Where it is desired to omit from a work-sheet 10 characters appearing upon certain writing lines of the original work-sheet 11, a carbon-sheet 27, like that shown in Figure 2, may be used, having, if desired, a side extension 28 at each side in which the slits or openings 21 are provided, so that 80 blank strips 25 and contrasting color strips 20 may be held in position, as upon the carbon-sheet 12.

In Figure 3 is also shown a wide strip 29, which is held in position by extensions 30 95 narrower than the strip but adapted to fit closely in the slits or openings 21 and 26, thus enabling a carbon-sheet 12 or 27, having slits for one width of strip, to be used with other wider strips, since extensions 30 100 100 may be made to fit any desired or standard size of slits 21 or 26.

To mount the strips 20 or 25 on the carbon-sheet indicated by 12^a in Figure 4, the carbon-sheet may be provided with projections 26^a to pass through perforations 26^b in strip 20^a. The projections 26^a may be folded over to retain the strip 20^a on the carbon-sheet 12^a.

Variations may be resorted to within the 110 scope of the invention, and portions of the improvements may be used without others.

Having thus described my invention, I claim:

1. A manifolding sheet comprising a carbon-sheet having a perforation, and a narrower overlying sheet connected to the carbon-sheet by a part passing through the perforation and holding said narrower sheet in position over the carbon-sheet to prevent 115 the underlying portion of the carbon face of the carbon-sheet from contacting with a work-sheet.

2. A carbon-sheet having means, including a plurality of perforations, for holding 125 the opposite ends of a narrower overlying sheet, to hold the latter in place, and to prevent the underlying surface of the carbon-sheet from contacting with a work-sheet.

3. The combination with a carbon-sheet 130

- having a slit, of a narrow strip having a different surface and overlying said sheet so as to prevent a portion thereof from contacting with a work-sheet, said strip having an end passed through said slit to hold it. 5
4. The combination with a carbon-sheet having a plurality of perforated slits at each end, of a strip having a manifolding surface of a different color, and insertible in said slits to be held in position thereby and overlie a section of the surface of the carbon-sheet, to become a substitute for the manifolding surface. 10
5. The combination with a carbon-sheet having extensions provided with slits, of a strip insertible in various pairs of said slits to overlie different selected sections of the carbon surface of the sheet, to prevent portions of the surface of the carbon-sheet from contacting with a work-sheet, said strip having a manifolding surface of a different color. 15
6. The combination with a carbon-sheet having an end extension provided with slits, of a strip insertible in one of said slits to overlie a strip of the carbon surface of the sheet, to prevent the surface of the carbon-sheet from contacting with a work-sheet. 20
7. The combination with a carbon-sheet having an end extension provided with offset slits, of a strip insertible in any of a plurality of said slits to overlie any one of a plurality of strips of the carbon surface of the sheet, to prevent a selected strip from contacting with a work-sheet. 25
8. The combination with a carbon-sheet having a black reproducing surface, of an extension of the sheet having staggered openings therein, and a strip having a red reproducing surface insertible in any of said openings to overlie selected portions of the black sheet surface. 30
9. The combination with a carbon-sheet having a black reproducing surface, of an extension at each end of the sheet, each extension comprising staggered openings so that they are paired off with each other, and a strip insertible selectively in said extension to overlie a stripe of the reproducing surface to keep it from contact with a work-sheet. 35
10. A manifolding sheet comprising a carbon-sheet and a detachable sheet connected to the carbon side of the carbon-sheet, said detachable sheet overlying a portion only of the carbon-face of the carbon-sheet so as to leave another portion of the carbon-face exposed and being movable as a unit with the carbon-sheet when it is laid with its carbon-face against a work-sheet. 40
11. A manifolding sheet comprising a carbon-sheet and a sheet overlying a portion of the carbon-face of the carbon-sheet and leaving another portion of said carbon face exposed, said overlying sheet being adjustable relatively to the carbon-sheet and being detachably mounted thereon for movement as a unit with the carbon-sheet when it is laid with its carbon face against a work-sheet. 45
12. A carbon-sheet having a plurality of perforations, and a narrow overlying sheet having reduced extensions to fit into the perforations. 50
13. A manifolding sheet having a carbon-face, in combination with a superposed strip formed to present a manifolding surface having a color different from that of the carbon-face of the manifolding sheet, said superposed strip being adjustable relatively to the manifolding sheet. 55
14. A manifolding sheet comprising a main carbon-faced sheet and an overlying sheet mounted on the carbon-face of the main sheet and being of less width than the carbon-sheet to expose a portion of its carbon-face, and connections between the end portions of the overlying sheet and the ends of the main sheet for causing the overlying sheet to move as a unit with the main sheet when it is laid with its carbon-face against a work-sheet. 60
15. A manifolding sheet comprising a main carbon-faced sheet and a sheet detachably connected to the carbon side of the main sheet, said detachable sheet being of less width than the main sheet and having one of its side edges spaced inwardly from the corresponding edge of the main sheet so as to leave a portion of the carbon-face of the main sheet exposed, and said detachable sheet being movable as a unit with the main sheet when it is laid with its carbon-face against a work-sheet. 65
16. A manifolding sheet comprising a main carbon-faced sheet and a sheet on the carbon-face of the main sheet and being of less width than the main sheet to expose a portion of its carbon-face, and connections between the overlying sheet and the main sheet for causing the overlying sheet to move as a unit with the main sheet. 70
